UNITED STATES PATENT OFFICE

133,862

DESIGN FOR A CHICKEN FEEDER

Robert Herbert Kinkel, San Antonio, Tex.

Application June 24, 1942, Serial No. 107,320

Term of patent 3½ years

To all whom it may concern:

Be it known that I, Robert Herbert Kinkel, a citizen of the United States, residing at San Antonio, in the county of Bexar and State of Texas, have invented a new, original, and ornamental Design for a Chicken Feeder, of which the following is a specification, reference being had to the accompanying drawing, forming part thereof.

Figure 1 is a top plan view of a chicken feeder showing my new design.

Figure 2 is a side elevational view, and

Figure 3 is a sectional view taken substantially on the line 3—3 of Figure 1.

I claim:

The ornamental design for a chicken feeder, as shown.

ROBERT HERBERT KINKEL.
